ATTORNEYS.

UNITED STATES PATENT OFFICE

WILLIAM H. KLEINHAMMER, OF SAN FRANCISCO, CALIFORNIA

WASHING MACHINE

Application filed September 19, 1928. Serial No. 306,855.

This invention relates generally to power driven machines for washing clothes, and particularly to machines of this type which utilize a rotatable or oscillating agitator or impeller removably positioned within a closed receptacle.

It is a general object of this invention to devise a simple but effective form of thrust bearing for use with the agitator of a clothes washing machine.

It is a further object of this invention to devise a thrust bearing particularly adapted for use with a reversible impeller, and which can be readily removed from one end of the impeller and attached to the other end.

It is a further object of this invention to devise a novel type of thrust bearing requiring no lubrication other than water or similar fluid.

20 It is a further object of this invention to devise a thrust bearing which will serve as a cushioning means to absorb vibration, and which will be practically indestructible.

It is a further object of this invention to 25 devise a thrust bearing for use with the agitator of a washing machine, which can be attached and readily removed from the agitator without removing screws or other similar attaching devices.

30 Further objects of the invention will appear from the following description in which I have set forth the preferred embodiment of my invention. It is to be understood that the appended claims are to be accorded a 35 range of equivalents consistent with the state of the prior art.

Referring to the drawing:

Figure 1 is a side elevational view illustrating my invention incorporated with the 40 agitator of a clothes washing machine.

Figure 2 is a side elevational view similar to Fig. 1, but showing the agitator in an inverted position.

45 Figure 3 is a perspective view in quarter cross section illustrating a thrust bearing device constructed in accordance with this invention.

This application is a continuation in part of subject matter disclosed in my co-pending 50 application Serial Number 59,280, filed Sep-

tember 29, 1925. In that application I disclose an improvement in agitators for washing machines of the general type disclosed and claimed in Patent No. 1,599,028, granted September 7, 1926. The invention herein disclosed and claimed is likewise an improvement of the invention covered by said Patent No. 1,599,028, although certain features of the invention are applicable to thrust bearings in general.

60 In the drawing I have shown a receptacle 10 within which is disposed an agitator or impeller 11. Receptacle 10 may be the usual container of a washing machine, or may be a permanent laundry tray. Agitator 11 in its 65 preferred form consists of a plate 12, preferably circular in contour, upon one side of which is formed a plurality of annular vanes 13. Formed centrally on opposite sides of the agitator, are the hubs 16 and 17, hub 16 70 extending beyond the lower surface of plate 12 and hub 17 extending a substantial distance beyond the vanes 13. For convenience in manufacture I prefer that the entire agitator structure be formed of a single casting 75 of some suitable metal such as aluminum.

To provide means for driving the agitator I have shown a non-circular driving shaft 18, having its upper end cooperatively associated with an arm 19, and its lower end extended through the hubs 16 and 17. The non-circular bore 21 formed in the agitator to admit the driving rod 18, is preferably of sufficient size that the rod is freely slidable with respect to the agitator. Rod 18 is likewise 80 slidably extended through the arm 19, so that it can be removed by lifting the same vertically from the agitator and through the arm 19, in order to permit removal of the agitator from the receptacle 10. Since the 85 non-circular bore 21 which receives the driving rod 18 extends entirely through the agitator 11, it is apparent that the agitator can be operated in an inverted position as shown in Fig. 2. This feature increases the utility 90 of the agitator, since when the agitator is in the position shown in Fig. 1, a greater agitation of the clothes is effected as is desirable when washing heavy fabrics, while in the 95 position shown in Fig. 2 it is best adapted for 100

the washing of silks and other similar light fabrics. I prefer to impart oscillatory movement to the agitator, and arm 19 therefore houses suitable motion imparting mechanism such as shown in Patent No. 1,627,053 issued to Morehouse and Haase.

If one or other of the hubs 16 and 17 is permitted to bear directly upon the bottom wall 22, it is apparent that the bottom will soon become worn, and a certain amount of vibration will be imparted to the receptacle from the agitator and driving rod 18. In my invention I provide a thrust bearing between the agitator and the bottom wall 22, and this bearing while being attached to the agitator so that it can be removed together therewith, merely has an abutting contact with the bottom of the receptacle. The form of thrust bearing which I prefer to employ is shown in Fig. 3 and consists of a block or body 23 made of resilient material such as a soft vulcanized rubber. One face of block 23 carries an integral collar 24 which is adapted to engage over an annular shoulder 26 formed upon the agitator, one shoulder being upon the hub 17, and the other upon hub 16. Because of the resilient nature of collar 24, the block 23 can be readily removed from one end of the agitator and attached to the other end as desired.

When an impeller or agitator to which a thrust bearing device of this character is attached is positioned within the receptacle 10, the lower face of block 23 rests upon the bottom wall 22 and supports the agitator. When the agitator is in normal operation the receptacle contains water, and as the fit between collar 24 and the corresponding shoulder 26 is a comparatively loose one, the surfaces in contact between the agitator and the block 23 are always lubricated by a film of water. The abutting contact between block 23 and the bottom wall 22 provides sufficient friction to maintain the block relatively stationary with respect to the receptacle, so that all relative movement occurs between block 23 and the agitator. When it is desired to invert the impeller, the block 23 can be removed from the agitator and attached to the hub at the opposite end of the agitator. Because of the resilient nature of the block 23 my thrust bearing device is not only indestructible, but it serves as a cushioning or shock absorbing means between the agitator and the receptacle, thus causing the washing machine to operate with less noise and less apparent vibration.

I claim:

1. In a washing machine, a receptacle, an agitator disposed within the receptacle, means for driving said agitator, and a thrust bearing of resilient rubber imposed between said agitator and the bottom of said receptacle.

2. In combination with a fluid agitator

adapted to be operably positioned upon a supporting surface, a hub formed upon said agitator, and a resilient rubber block, a portion of said block interlocking a portion of said hub, said block forming a thrust bearing between said hub and said support. 70

3. In combination with a fluid agitator adapted to be operably positioned upon a supporting surface, a hub formed upon said agitator, an annular shoulder formed about the end of said hub, and a resilient rubber block, said block having a collar formed to engage over said shoulder and detachably retain the block upon the end of the hub, said block forming a thrust bearing between said hub and said support. 75

4. In a washing machine, a receptacle, a drive shaft therein, an agitator positioned upon said drive shaft, a hub formed upon said agitator, said hub having an annular shoulder, a rubber block adapted to be positioned between said agitator and a side of said receptacle to act as a thrust bearing, said block having a collar formed to engage said shoulder to detachably retain said block on said hub. 80

5. In a washing machine, a drive shaft, an agitator reversibly positioned upon said shaft, an extending member at one end of said agitator, and a hub extending from the other end of said agitator, said hub and said member having annular shoulders formed at substantially their extremities to provide supporting bearing surfaces for said agitator. 95

6. In a washing machine including a receptacle having a stationary bottom, a drive shaft, an impeller engaged with said drive shaft, and a bearing detachably engaged with said impeller, said bearing being of a resilient material and normally resting upon the bottom of the receptacle to be lifted when the impeller is lifted. 100

7. In a washing machine including a receptacle having a stationary bottom, a drive shaft, an impeller engaged with said drive shaft, and a rubber bearing detachably engaged with said impeller, said bearing normally resting upon the bottom of the receptacle to be lifted when the impeller is lifted. 110

8. In a washing machine including a receptacle having a stationary bottom, an agitator, a hub formed upon each side of said agitator, and a thrust bearing device detachably engageable with either one of said hubs, said device normally resting upon the stationary bottom to serve as a thrust bearing. 115

9. In a washing machine including a receptacle having a stationary bottom, an agitator having a hub, and a thrust bearing device formed of resilient material cooperatively associated with said hub, said device normally resting upon the stationary bottom of the receptacle. 125

10. In combination with a receptacle having a stationary bottom, a fluid agitator hav- 130

ing a hub, a thrust bearing device of resilient rubber detachably retained upon said hub by the resilience of said rubber, said device normally resting upon the stationary bottom.

- 5 11. In a washing machine employing an agitator in a receptacle having a stationary bottom, a circular hub formed on the agitator, a thrust bearing device comprising a resilient body adapted to be slipped onto the circular hub to be retained by the resiliency of the body on the agitator, and to be interposed between the agitator and the stationary bottom.
- 10 12. In a washing machine utilizing a receptacle having a stationary bottom and a driving mechanism, an agitator adapted to be positioned in either of two positions with respect to the driving mechanism and adapted to be driven thereby, and separate bearing surfaces formed on the agitator and adapted to support the agitator on the stationary bottom when the agitator is in either of said positions.
